US00D774547S

(12) **United States Design Patent** (10) Patent No.: **US D774,547 S**
(45) Date of Patent: **** Dec. 20, 2016**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Jay Christopher Capela**, Santa Cruz, CA (US); **Gustaf Engstrom**, Cupertino, CA (US); **Gary William Gehiere**, Santa Clara, CA (US); **Markus Hagele**, San Francisco, CA (US); **Alexander Charles Maclean**, San Jose, CA (US); **Charles Janusz Migos**, Millbrae, CA (US); **Martin J. Murret, II**, Portland, OR (US); **Brett Rampata**, Cupertino, CA (US); **Allison Styer**, San Francisco, CA (US); **Eddie Shawn Wilson**, Midlothian, VA (US)

(73) Assignee: **APPLE INC.**, Cupertino, CA (US)

(**) Term: **15 Years**

(21) Appl. No.: **29/540,715**

(22) Filed: **Sep. 27, 2015**

Related U.S. Application Data

(63) Continuation of application No. 29/468,732, filed on Oct. 2, 2013, now Pat. No. Des. 748,147, which is a continuation of application No. 29/457,359, filed on Jun. 10, 2013, now Pat. No. Des. 740,851.

CLAIM

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of an display screen or portion thereof with graphical user interface showing our new design; and, FIG. 2 is a front view of another embodiment thereof.

The broken lines in the figures show a display screen or portion thereof, and form no part of the claimed design.
